CLAIM

The ornamental design for a distiller, as shown and described.

DESCRIPTION

FIG. 1 is an elevation view of the front of a distiller constructed in accordance with one preferred embodiment of the invention;

FIG. 2 is an elevation view of the right side of the distiller shown in FIG. 1, the elevation view of the left side of such distiller being a mirror image thereof;

FIG. 3 is an elevation view of the rear of the distiller shown in FIGS. 1 and 2;

FIG. 4 is a top plan view of the distiller shown in FIGS. 1-3; and,

FIG. 5 is a bottom plan view of the distiller shown in FIGS. 1-4.

The broken lines on portions of the distiller are for the purpose of illustrating unclaimed environmental structure only.
